UNITED STATES PATENT OFFICE.

ERNEST RICHARDSON, OF BEAVER FALLS, PENNSYLVANIA.

WATER-CLOSET STRUCTURE.

Application filed October 11, 1924. Serial No. 742,988.

This invention relates to water closet seats, and also to the lids thereof, the objects of the invention being to construct these elements, so that they will be light and durable, inexpensive to manufacture, sanitary in use, and clean, neat and attractive in appearance. With these and other objects in view, the invention consists of the novel features of construction and combination of parts described in detail in the specification to follow and pointed out in the appended claims.

In the accompanying drawings:

Fig. 1 is a plan view partly in section of the improved seat and lid.

Fig. 2 is a longitudinal sectional elevation of the same on the line 2—2 of Fig. 1.

Fig. 3 is a sectional elevation of the two plates of which the seat is formed, showing said plates separated from each other.

Fig. 4 is a similar view showing said plates welded together.

Fig. 5 is a perspective view on an enlarged scale of the rear end of the seat structure and the parts of the seat hinge separated from each other.

Fig. 6 is a perspective view of the rear end of the seat showing the seat hinge attached thereto.

Fig. 7 is a longitudinal section through the same on the line 7—7 of Fig. 6.

Fig. 8 is a fragmentary view of the bottom plate of the lid showing the same formed with an opening to receive a cushion block, which latter is shown in position therein in dotted lines.

Fig. 8^a is a side elevation of the cushion block.

Fig. 9 is a view similar to Fig. 8 showing in dotted lines a cushion block of modified form.

Fig. 9^a is a side elevation of the modified form of block.

Referring to the drawings:

In the embodiment illustrated, the improved seat 1 is constructed of comparatively thin sheet metal and consists of a substantially flat base section or plate 2 of ring-like form, and a top section or plate 3 of similar form but having flanges 4 and 5 at its inner and outer edges curved downwardly to meet the marginal edges of the base plate 2. The two sections or plates are welded together along their meeting edges as at 4^a, Fig. 4, so as to form an integral union or connection between them, any bulge or piling up of the metal due to the welding operation being

dressed down to leave a smooth uninterrupted surface. There is thus produced a hollow metallic seat structure integral throughout and free from seams or joints, which feature is advantageous not only in giving the finished seat a neat and attractive appearance, as well as making it sanitary but also in facilitating the enameling process to which the seat is subjected as presently described.

At the rear end of the structure, the outer flange 5 of the top plate 3 is cut away, as best seen in Figs. 5 and 7, to provide an opening 6 extending across the seat for nearly the full width of the same. The main purpose of this opening is to permit the application of the hinge parts by which the seat is pivoted to the bowl A, but it subserves other and important advantages. For example, by inserting a holder or handle of some sort in the opening 6, the seat may be supported without obstructing any portion of its surface, so that the entire surface of the seat is left exposed for the smooth and unblemished application of the porcelain enamel coating. Before applying such coating, it is proposed to immerse the seat in a pickling bath in order to cleanse the metal surfaces and prepare them for the reception of the coating. The opening 6 is also useful in this connection, since it provides an escape for the pickling solution after the seat has been removed from the bath.

The hinge structure for the seat consists of an exterior metal hinge plate 7 and an interior metal supporting plate 8. The supporting plate 8 rests at its lower edge on the base plate 2 and engages at its upper edge and at its opposite ends the inner face of the hollow body surrounding the opening 6, closing the same entirely. The hinge plate 7 engages the outer face of the hollow body around the opening 6, entirely covering the same, and is formed with a flange 7^a underlying the rear free edge of the base plate, to brace the same. The opening 6 is thus effectually closed against the entrance of dirt or débris, so that the seat will be perfectly sanitary and present a neat finished appearance. Screws 9, which extend through holes in the ends of the hinge plate, and through the opening 6, are threaded into the ends of the supporting plate, whereby the parts may be drawn tightly together and the hinge plate clamped firmly and solidly.

in position on the rear end of the seat. By these means, the hinge parts may be attached to the enameled and finished seat without the necessity of forming openings 5 or holes therein to receive the fastening devices which would crack and mar the enamel coating. Lugs 10 project rearwardly from the hinge plate and are formed with aligned bearing openings through which is extended 10 a pivot rod 11 passing through bearing openings in the usual heads 12 fixed to and projecting upwardly from the rear end of the bowl.

The detailed form and construction of the 15 parts of the seat structure as above described apply equally as well to the lid 14, the only difference being that the lid consists of a base plate 15 of disk-like form and a top plate 16 of similar form, these two plates, 20 when welded together as described in the formation of the seat, providing a flat hollow integral metal lid structure of a form and size which will cover the central opening in the seat. At its rear end, the lid is 25 formed with an opening 17 subserving the same functions and advantages as the opening 6 in the rear end of the seat structure. In this instance, the hinge structure comprises a hinge plate 17, a supporting plate 30 18 and clamping screws 19 similar to the corresponding hinge parts of the seat structure. Lugs 20 project rearwardly and downwardly from the hinge plate 17 and are formed with bearing openings mounted 35 on the pivot rod 11, whereby the lid is hinged to the seat so that it may be opened and closed as usual.

Buffer blocks 21, preferably made of rubber, are applied to the under side of the lid 40 in position to rest upon the upper side of the seat, and thus cushion the closing movement of the lid. As shown in Figs. 8 and 8^a, the base plate of the lid is formed with a hole 22 and the buffer block is formed with a 45 cylindrical head 23 of greater diameter than that of the hole, which head when crowded into the hole will expand on the inner side of the plate and hold the block in place. A similar block 21^a but of slightly different 50 form is shown in Figs. 9 and 9^a, where it will be seen that the head 23^a of the block is of sloping or wedge form to enter the hole 22^a.

The closet seat and lid constructed in the 55 manner described are light, strong and durable, and free from joints, seams, crevices or other surface obstructions. Due to the smooth and unobstructed surface of the seat, the enamel coating may be applied uniformly and smoothly to provide an unblemished and pleasing polished surface which 60 may be kept perfectly clean and sanitary. The hollow character of the seat enables the body of air enclosed by the thin metal walls 65 to assume readily and quickly the tempera-

ture of the room, so that the metallic character of the seat will cause no discomfort to the user. However, if desired, the seat may be filled with some suitable insulating material, the integral character of the seat being well adapted to the use of such material. The hinge structure is firmly and solidly attached to the seat solely by the clamping action of the hinge plate and supporting plate on the edges of the opening 70 formed in the rear flange of the seat, thereby avoiding the necessity for the formation of holes or sockets in the finished structure to receive hinge fastening devices. These 75 and various other advantages will be readily appreciated.

In the embodiment herein illustrated, the hollow seat is made up in continuous ring-like form, but it is obvious that it might partake of any other conventional form 80 without departing from the spirit of this invention. For instance, in applying the invention to that conventional form of seat which presents two complementary members connected at the rear to a common hinge 85 structure, each member would be made of two plates welded together in the manner described and provided with an opening at the rear for the attachment of the hinge parts as before. In such case, the supporting plate would be divided into two sections, one for each seat member. As a matter of fact, even in the embodiment illustrated, the supporting plate might be divided 90 into two end sections, instead of being made in one piece as shown. It may also be noted that the sheet metal plates or sections which compose the seat may be made or stamped 95 out in various forms and welded together in the desired manner, the particular form illustrated being merely by way of example. Such variations and others will readily suggest themselves to those skilled in the art and still be comprised within the scope of 100 the invention. It should be understood, therefore, that the invention is not limited to any particular form or construction of the parts except in so far as such limitations are specified in the appended claims.

The term "water closet element" occurring 105 in certain of the claims is a generic expression intended to describe either the seat or the lid of the water closet structure, the constructions defined by said claims being present 110 alike in both elements.

Having thus described my invention, what I claim is:

1. A water closet element comprising a hollow metal body provided at its rear end with an opening leading to the interior thereof, in combination with a hinge structure clamped to the marginal edges of said opening, said hinge structure comprising a supporting element located within the hollow metal body, and the opening in the rear 120

end of said body being of sufficient size to permit the insertion of the hinge supporting element into the interior of the hollow metal body.

- 5 2. A water closet element comprising a hollow metal body provided at its rear end with an opening leading to the interior thereof, in combination with a hinge structure attached thereto, said hinge structure 10 comprising a supporting plate engaged with the inner side of the body adjacent the opening therein, said opening being of sufficient size to permit the insertion of the supporting plate into the interior of the hollow metal 15 body, a hinge plate opposed to the supporting plate and engaged with the outer side of the body, and means connecting the two plates together through the opening in the body.
- 20 3. A water closet element comprising a hollow metal body formed at its rear end with an opening leading to the interior thereof, in combination with a supporting plate disposed within the body and engaged 25 with the inner side of the same adjacent said opening, said opening being of sufficient size to permit the insertion of the supporting plate into the interior of the hollow metal body, a hinge plate engaged with the outer 30 side of the body adjacent the opening and opposed to the supporting plate, and clamping screws passing through the opening in

the body for connecting the two plates together.

4. A water closet element constructed of 35 sheet metal comprising a base plate and a top plate having downturned flanges integrally connected at their edges to the marginal edges of the base plate to form a hollow integral structure, the rear flange of the top 40 plate being cut away between its ends to form an opening in the rear end of the structure leading to the interior thereof, and of sufficient size to permit the insertion into the interior of the hollow structure of one 45 element of a hinge structure adapted to be clamped to the edges thereof.

5. A water closet element comprising a hollow metal body provided at its rear end with an opening leading to the interior 50 thereof, in combination with a hinge structure clamped to the marginal edges of said opening, said hinge structure including a supporting plate arranged within the metal body in engagement with the marginal edges 55 of the opening and a hinge plate fully covering said opening, said opening being of sufficient size to permit the insertion of the hinge supporting plate into the interior of 60 the hollow metal body.

In testimony whereof, I have affixed my signature hereto.

ERNEST RICHARDSON.
